FIG. 3.

Inventor.

36 Henry F. Flowers

Say Sturtevant & Mason Attorneys

UNITED STATES PATENT OFFICE.

HENRY FORT FLOWERS, OF FINDLAY, OHIO.

DUMPING DEVICE.

Application filed November 19, 1925. Serial No. 70,076.

This invention relates to improvements in vehicle dumping devices of the stationary type which serve for dumping vehicles having tiltable bodies mounted upon an underframe.

In previous dumping devices of this type, it has been customary to invert or tilt the vehicle as a whole by means of a cradle or rocking frame, into which the vehicle was driven and clamps applied to prevent the separation of vehicle and dump structure. In some cases, the vehicle has been designed so that its trucks are held in position by a permanent and rigid structure adjacent the dumping point, while the body makes the necessary dumping movement.

As distinguished from these former devices, the present invention presents a structure by which the vehicle underframe remains stationary and which has clamping and dumping devices movable into and out of operative position and when in non-operative position are entirely free of and not in any possible contact with a vehicle either entering or leaving the dumping position.

A further object of the invention is to provide a simple and compact mechanism to move the dumping and clamping structure into and out of operative position.

Another object is to provide alining and centering devices to return the dumping structure to the identical initial position after each operation.

Still another object is to provide a clamping device which adapts itself to the angle of the vehicle body during dumping and is thus prevented from buckling or distorting the vehicle body.

A further object is to provide means for automatically and positively releasing the clamping structure from the vehicle body dumping structure when the two are in the correct relative position for dumping, and for returning the two structures for cooperation after completion of the dumping movements, so that they may be simultaneously and co-operatively removed from the path of the vehicle.

With these and other objects in view, as will appear in the course of the following specification and the accompanying drawings, there has been represented in the latter one form of execution of the mechanism, in conjunction with a dump car having trucks mounted upon rails, and a body adapted to

tilt in either direction for dumping and itself having closing doors which are automatically opened and closed during the dumping and return of the body.

Fig. 1 shows the dumping mechanism in the non-operative position, with a car upon the dumping chute platform.

Fig. 2 shows in full lines the same mechanism after movement into the operative position, and in dotted lines the dumping mechanism in the titled position of the car body.

Fig. 3 is a view in side elevation of the car, with the mechanism in operative position.

Figs. 4 and 5 are detail views in section approximately on line 4—4 of Fig. 3, showing the clamping structure in different positions.

In these figures, the dumping or discharge chute 10 is represented in section, with the top girders 11 mounted thereon, which in turn support the rails 12. The dump car is supported upon the wheels 13 which run on these rails and carry the trucks and underframe represented generally at 14. Carried by the brackets 15^b at either side of the underframe is arranged a hold-down bar 15, 15^a and at suitable points of the underframe are disposed the two trunnions 16 and 16^a, which are symmetrical with each other and equally distant from the central longitudinal axis of the car. The dump body represented generally at 17 is mounted upon these trunnions as fulcrums for its tilting toward the respective side. It will be understood that it is preferred to provide some clamping or locking means between the car underframe, the trunnions, and the clamp body proper, so that the latter will not be detached from the underframe during the shocks and movements incident to discharge:

for this purpose may be employed any suitable construction, but preferably that shown in my copending applications Serial Number 740,307, filed on September 27, 1924, and Serial No. 66,791, filed on Nov. 4, 1925, to which reference may be made for a detailed description of the locking means which are here indicated generally at 18. The body 17 is provided with the hinged doors 17^b at each side, which have the pivots 17^a and are connected by links 18^a to the securing links 18, as set forth in the aforesaid applications: in this wise, when the car body is tilted to-

ward either side, the corresponding door is automatically swung about its pivot to permit the discharge of the load in the body.

It will be understood that this car assembly of wheels, underframe, trunnions and dump body may be propelled along the rails from the loading to the discharge point in any suitable manner, and that it may be provided with the customary accessory apparatus such as brakes.

The dump body has a floor 19 of sheet metal which is curved downwardly at each side into a normally vertical depending flange 20. The car body rests upon the trunnions 16 and 16^a by means of a series of gusset plates 22 which are rigidly secured to the car floor, as by welding. The outer ends of these gusset plates and the push-up bar 21 are secured together for mutual reenforcement by the respective plates 23 which are welded to each.

A cross-balk 30 beneath the girders 11 carries the operating mechanism for the dumping device. The electric motor 31 is preferably of a standard electric railway design, and by means of a suitable gear train contained within the casing 32 drives the intermediate gear 33 in one direction or the other according to the regulation of the current delivered to the field and armature of the motor. This intermediate gear 33 is journaled upon the cross-balk 30 for rotation about its own axis, and carries upon its shaft 34 a pinion 35 which is keyed thereto for positive driving thereby. The bullwheel 36 is mounted on a shaft 37 journaled for rotation about its own axis upon the cross-balk 30; and by means of the teeth on the periphery of the bullwheel 36 it is in driven engagement with the pinion 35. When the electric motor 31 is operated in one direction or the other, the bullwheel 36 is driven in a corresponding direction by means of the reduction train 32, the intermediate gear 33 and the pinion 35.

Pivotedly mounted upon the shaft 37 of the bullwheel 36 are a pair of radius arms 38 which have the hooks 39 formed on their upper ends at the side adjacent the rails, and which are so designed that these hooks are loosely but closely received over the hold-down bars 15 of the respective cars, when the radius arms 38 are moved to the operative position shown in full lines in Fig. 2. At the upper ends, these two radius arms 38 are connected by an apron 40 which is welded to the upper ends of each of the arms and extends substantially parallel to the shaft 37 between the arms.

Pivotedly mounted on the ear 41 forming an offset of one arm 38 is a lever 42 which normally is in a lowered position by the action of gravity or a suitable return device not shown. A link 43 is jointed to this lever 42, and extends through a guide mem-

ber 44 on the arm 38 into operative engagement with the teeth on the bullwheel 36. It will be understood that when the bullwheel is moved in a counter-clockwise direction from the position shown in Fig. 1, the link 43 is located between two of its teeth, as shown in this figure, and the radius arms 38 are positively moved in a counter-clockwise direction until the hooks 39 are presented above the hold-down bar 15 on the car underframe. During this movement, the lever 42 comes into contact with the hold-down bar 15 and is prevented from further movement, so that it finally assumes at its upper end a position parallel to the advancing edge of the arms 38, as shown in Fig. 2. During this movement of the lever 42, the link 43 is raised out of engagement with the teeth on the bullwheel 36, and the latter is thereby liberated from any engagement with the radius arms 38 and may thereafter continue to move in a counter-clockwise direction independently of these arms, during which time the radius arms 38 remain resting against the hold-down bar 15, by reason of the fact that the weight of the material in these arms and associated parts has been moved so that its center of gravity is beyond a vertical plane passing through the axis of the shaft 37. It may be remarked that in the event of an insufficient engagement of the hook 39 and arms 38 with the bar 15, the lever 42 will return and present its link 43 into engagement with the teeth on the bullwheel 36, until the final predetermined position has been attained.

After the release of the radius arms 38 from the bullwheel 36 has occurred, the bullwheel 36 continues to revolve in a counter-clockwise direction. A pin 45 is fastened solidly to the rim of the bullwheel 36, and serves as a pivot for the push link 46, which has the enlarged bearing member 47 supported on this pin 45 loosely revoluble with regard thereto. On the outer end of the pin 45 is a collar 48 which is keyed to the pin 45. A control link 49 is pivoted to the collar 48 at 40, and extends upwardly therefrom in a direction substantially parallel to that of the push link 46.

The push link 46 is preferably hollow as shown in Figs. 4 and 5, and has mounted at its upper end the shackle 51 which has a socket 52 therein fitted for cooperation with the push-up bar 21 on a car. A retaining hook 53 is pivoted in the shackle 51 by a shaft 54 to which it is keyed and which turns freely in apertures of the shackle. A crank arm 55 is keyed to the shaft 54 at the exterior of the shackle, and at its outer end is jointedly connected to the control link 49. When an upward thrust occurs upon the crank arm 55 with relation to the shackle 51, the hook 53 is rotated clockwise from the position of Figure 4 to the position of

Fig. 5, in which it engages the push-up bar 21. It is preferred to secure the hollow push-link 46 and the shackle 51 together by means of the alining pin 56 which is substantially parallel to the shaft 37, and as shown in Figure 3, extends for substantially the spread of the apron 40. This apron, as shown in Figs. 1 and 2, has notches 57 in its upper edge for receiving and guiding the alining pin 56 into the identical lowered position after each operation of dumping, which assures that the socket 52 in the shackle 51 will always be presented in the proper relation beneath the push-up bar 21 of each succeeding car.

In order to support the under-frame of the vehicle against torsional strain during tilting, an automatically positioned support is provided. The lever arms 70 carry at their tops a bar 71 extending parallel to the track in this embodiment adapted in the raised position to come close to or into slight engagement with the underframe 14, and are pivoted at 72 to the chute framing 11. Likewise pivoted relative to the chute framing 11 are the operating cranks 73 and the levers 74, the latter with the link 75 forming a toggle to hold the lever arms 70 in raised position at the full extension of the toggle. The levers 74 are connected by the links 76 to one end of the cranks 73, and the other ends of the latter are in turn positively connected by the links 77 with the radius arms 38 at pivots 78.

The operation of the device is substantially as follows:

A car is moved to a position upon the rails 12 such that the hold-down bar 15 and the push-up bar 21 upon the respective side of the car are presented opposite the radius arms 38. The motor 31 is then set in operation, and the bullwheel 36 moves in a counter-clockwise direction until the radius arms 38 are presented against the hold-down bar 15, with their hooks 39 extending thereto: at this time, as set forth above, the lever 42 has caused the release of the radius arms 38 from the bullwheel 36. The bullwheel 36 continues to revolve in a counter-clockwise direction under the actuation of the electric motor 31. During this movement, the pin 45 at first has a very small acceleration vertically, whereas the pivot 50 mounted on the collar 48 has a greater acceleration vertically, since it is several degrees in advance of the pin 45. As a result of this procession, a thrust is exerted upon the control link 35 which causes the crank arm 55 to make an oscillation with regard to the shackle 51, by which the hook 53 is moved from the position shown in Fig. 4 to that shown in Fig. 5. As the pin 45 passes the plane through the axis of shaft 37 which is perpendicular to the direction of the

push-link 46, the movement of the control link 49 becomes less than the movement of the push-link 46: as the result of which the hook 53 is slightly retracted, but not for a sufficient distance to release the push-up bar 21 from the socket 52. The result of this retrograde movement of the hook 53 is to prevent the hook from being forced against the depending flange 20 of the car floor, which might result in a buckling of the floor flange. The hook 53 assures at all times that the car body is positively connected to the push-link 46.

In this way, the adjacent side of the car body is raised, and the load on the body is discharged at the opposite side into the chute 10. It will be understood that it is preferred to provide an automatic door opening system, by which the door at the appropriate side of the car is caused to open automatically during the raising or tilting of the body, as represented in Fig. 2. At the final raising and dumping position, the car body and its doors, the push-link 46 and the control link 49 are in the position shown in dash lines in Fig. 2.

During the counter-clockwise movement of the radius arms 38, the links 77 are pushed to rock the cranks 73, and these in turn push the links 76 to straighten out the toggle 74, 75. This latter straightening causes the lever arms 70 to be rocked upwardly to present the bar 71 beneath the vehicle underframe 14. As the dump body tilts and the center of gravity shifts towards the lower side, this side is supported upon the underframe 14 by the trunnions 16. The underframe 14 is solidly supported by the bar 71, and no torsional strain is transmitted from the center of the vehicle towards the wheel trucks.

When the mechanism has reached the position shown in dash lines in Fig. 2, the motor 31 is brought to a standstill preferably by means of a limit switch not shown. The car body may now be returned to the initial or transport position by reversing the direction of travel of the motor 31, so that the bullwheel 36 is driven by the same reduction gear train in a clockwise direction. As a result of this clockwise movement of the bullwheel 36, the push-link 46 is withdrawn downwardly, and drags the car body with it, by reason of the engagement of the hook 53 upon the push-up bar 21, irrespective of the position of the center of gravity of the car body and any residual load thereon. The car body is thus positively returned to its transport position. During the downward movement of the push link 46, the control link 49 operates the crank 55 in a reverse manner to that set forth above, and finally, when the control link 49 and push link 46 have reached the approximate posi-

tion shown in full lines in Fig. 2, the hook 53 releases the push-up bar 21. Thereafter, the push-link 46 makes a slight further downward movement, and the ends of its pin 56 encounters the guiding notch 57 in the apron 40, so that the shackle 51 is brought back to the identical initial position.

During this return movement, the radius arms 38 have remained stationary, and hence 10 the bar 71 has continued in supporting relation to the underframe.

At substantially this moment, a plunger plate 60 which has a guide stem 61 held in an ear 62 on the bullwheel 36 by means of 15 a pin 63, comes in contact with one of the arms 38. A spring 64 is provided between the ear 62 and the plate 60 to soften the shock of impact. Since there is no longer a load upon the shackle, which has cleared 20 the push-up bar 21 and all other parts of the car, the arm 38 is gently moved in a clockwise direction by the rotation of the bullwheel 36 and its plunger plate 60. As the radius arms 38 move in this clockwise 25 direction, the weight of the lever 42 causes it to remain pressing against the hold-down bar 15, in which manner the link 43 is caused to move downward and engage with the teeth on the periphery of the bullwheel 36, thus locking the radius arms 38 and 30 associated parts to the bullwheel 36 for positive movement therewith. The radius arms 38 are thereafter positively swung to the 35 non-operative position shown in Fig. 1, in which there is no possibility of contact between any parts of the car with any parts of the dumping mechanism and are brought to a standstill by stopping the motor 31 preferably by a second limit switch.

40 The arms 70 and bar 71 have meanwhile been returned to the lowered position, out of the way of the trucks and other parts of the vehicle, by the traction of links 77 upon the cranks 73, and of these in turn by the 45 links 76 upon the toggle 74, 75.

The car may now be transported away 50 from the dumping position above the chute 10, and a new car moved into that position for dumping, which operation is accomplished in the manner above indicated.

55 It will be particularly observed that although there is a great shock upon the car body as the load leaves the upper side of the tilted car and moves the center of gravity toward the other side, which normally would tend not only to carry the body completely over about the trunnion 16, but also would serve to press downwardly at this trunnion upon the underframe 14 of the car 60 and raise the opposite side of this underframe, yet by the present construction, the hooks 39 on the radius arms 38 are brought into close engagement with the hold-down bar 15 and the bar 71 is presented to sup-

port the underframe at the point near where the greatest loading occurs, to prevent a twisting or distortion of the underframe of the car: while the push link 46 is positively locked to the car body by the hook 53. It is apparent, therefore, that very little strain is placed upon the underframe or body of the car which might tend to twist these members, and therefore the said members may be made much lighter than heretofore: since the bar 71, the socket 52 and the 65 hooks 39 engage the underframe and body approximately midway between the trucks, this action occurs at the location of the 70 greatest tendency towards twisting.

75 Obviously changes may be made in the design and arrangement of the several parts without departing from the invention as set forth in scope by the appended claims.

Having thus described my invention, what I claim is:—

80 1. In a dumping device for vehicles having an underframe and a dump body adapted to tilt thereon for side dumping, devices to engage the underframe and hold the same against movement during dumping, said holding devices being movable into engagement with said underframe and out of engagement therewith into a position clear of the said underframe for the entrance or removal of said vehicle with regard to said device, means to move said holding devices into and out of engaging 85 position, devices to raise the adjacent side of the dump body, and devices actuated in unison with said raising devices to lock said dump body to said raising devices to prevent 90 upsetting of the dump body during dumping. 95

100 2. In a dumping device for vehicles having an underframe and a dump body adapted to tilt thereon for side dumping, guide devices to present the vehicle at a predetermined position in said device, devices to engage the underframe and hold the same against movement during dumping, devices to raise the adjacent side of the 105 dump body, and devices actuated in unison with said raising devices to lock said dump body to said raising devices to prevent upsetting of the dump body during dumping.

110 3. A dumping device for vehicles having an underframe and a body carried thereby and adapted to be tilted for dumping, comprising devices for engaging the underframe and holding the same from movement during the relative tilting of the body, devices for engaging and raising the body to dumping position, and means to simultaneously 115 position said holding and raising devices.

120 4. A dumping device for vehicles having an underframe and a dump body adapted to be tilted thereon for side dumping, comprising an actuating mechanism, devices operated thereby for automatically engaging the 125

underframe of the car and holding the same during dumping, and devices automatically operated by said actuating mechanism for engaging the dump body for raising the same to dumping position. 5

5. A dumping device for vehicles having an underframe and a dump body adapted to be tilted thereon for side dumping, comprising an actuating mechanism, devices 10 operated thereby for automatically engaging the underframe of the car and holding the same during dumping, and devices automatically operated by said actuating mechanism for engaging the dump body for raising 15 the same to dumping position, said raising means being provided with means for engaging and holding the body from upsetting.

6. In a dumping device for vehicles having an underframe and a dump body adapted 20 to tilt thereon for side dumping, a hold-down arm, means to swing said arm into engagement with the underframe, a push-up link, said means serving to move said push-up link into engagement with said dump 25 body and to actuate said push-up link to raise the adjacent side of the car body.

7. In a dumping device for vehicles having an underframe and a dump body adapted to tilt thereon for side dumping, 30 a bullwheel, a hold-down arm, means to connect said bullwheel and said arm for cooperative movement to present said arm in engagement with the underframe, a push-up member, said arm presenting said member 35 into operative relation with the dump body, and a connection between said bullwheel and said member to raise the adjacent side of the dump body during a further movement of the bullwheel after presentation of said arm 40 upon said underframe.

8. In a dumping device for vehicles having an underframe and a dump body adapted to tilt thereon for side dumping, a hold-down member, a push-up member, a locking 45 member, and common means to position said hold-down member in engagement with the underframe, then to position said push-up member and said locking member in engagement with said dump body, and finally to 50 tilt the dump body for dumping.

9. In a dumping device for vehicles having an underframe and a dump body adapted to tilt thereon for side dumping, a hold-down member, a push-up member, common 55 means to successively position said hold-down member in engagement with said underframe and to actuate said push-up member to tilt the dump body, and means upon said hold-down member to guide and 60 align said push-up member into its lowered position.

10. In a dumping device for vehicles having an underframe and a dump body adapted 65 to tilt thereon for side dumping, a bullwheel, a hold-down member, means to connect said

bullwheel and said hold-down member for simultaneous movement for the engagement of said member with the underframe, and a trip to release said connecting means upon the engagement of said member with said 70 underframe.

11. In a dumping device for vehicles having an underframe and a dump body adapted to tilt thereon for side dumping, a hold-down member, a push-up member, and 75 a mechanism to successively present said hold-down member in engagement with the underframe to prevent movement thereof during dumping and to actuate said push-up member for raising the dump body for 80 dumping during operation of said mechanism in one direction, and to successively return the push-up member to lowered position and to remove the hold-down member 85 from the path of the vehicle during operation thereof in the other direction.

12. In a dumping device for vehicles having an underframe and a dump body adapted to tilt thereon for side dumping, a hold-down member, a push-up member, a mechanism to successively present said hold-down member in engagement with the underframe to prevent movement thereof during dumping and to actuate said push-up member for 90 raising the dump body for dumping during operation of said mechanism in one direction, and to successively return the push-up member to lowered position and to remove the hold-down member from the path of the vehicle during operation thereof in the other direction, and a device actuated by said mechanism to lock said dump body to the 95 push-up member while in the raised position.

13. In a dumping device for cars having an underframe and a dump body adapted to tilt about a trunnion of said underframe for side dumping, a bullwheel, a pair of radius arms loosely pivoted about the axis of said bullwheel, hooks formed integrally with said arms to engage the underframe 100 of the car, a pin on the periphery of the bullwheel parallel with its axis, a push-up link journalled upon said pin, a second pivot pin attached to said bullwheel in advance of said first pin, a control link 105 journalled upon said second link, a shackle upon said push-up link adapted to engage the dump body, a hook in said shackle adapted to cooperate therewith to lock 110 said dump body to said push-up link, said control link being connected operatively to said hook to actuate the same, a trip lever on said arms, a locking link connected to said trip lever and normally engaged with 115 said bullwheel to lock said arms thereto, said trip lever being adapted to withdraw said locking link from said teeth upon engagement of said arms and hooks upon the 120 underframe, said bullwheel and pins upon further movement of said bullwheel serving 125

130

to actuate said push-up link to tilt the dump body and to lock said push-up link to said dump body and upon reversal of such movement to lower and return said dump body, 5 means upon said arms to guide said push-up link to the identical initial position, and a device upon said bullwheel to move said radius arms away from said underframe after the completion of the lowering of the 10 dump body.

14. In a dumping device for vehicles having an underframe and a dump body adapted to be tilted thereon for side dumping, said body having a depending flange and a 15 bar thereon, a push-up member, mechanism to present said member against the bar and to raise the dump body into a tilted dumping position, a locking device actuated from said mechanism to lock said body to said 20 member during raising, said locking device having a retrograde movement during the final tilting to remove it from pressing against the depending flange.

15. In a dumping device for vehicles having an underframe and a dump body adapted to tilt thereon for side dumping, a device to raise one side of said dump body, a device to support said underframe adjacent the lower side during tilting, and a mechanism 30 to bring said devices into and out of operative positions simultaneously.

16. In a dumping device for vehicles having an underframe and a dump body adapted to tilt thereon for side dumping, a device to raise one side of said dump body, a device 35 to hold down the adjacent side of the underframe, a device to hold up the opposite side of the underframe, and a mechanism to bring said devices into and out of operative positions 40 simultaneously.

17. In a dumping device for vehicles having an underframe and a dump body adapted to tilt thereon for side dumping, a device to raise one side of said dump body, a device 45 to hold down the adjacent side of the underframe, a device actuated from said holding device to support the opposite side of the underframe, and a mechanism to bring said device into and out of operative positions 50 simultaneously.

18. In a dumping device for vehicles having an underframe and a dump body adapted to tilt thereon for side dumping, a device to support the side of the underframe adjacent the lowered side of the dump body, a device to hold down the opposite side of the underframe, means to raise one side of the dump body, mechanism to move said devices into and out of operative positions, 55 said mechanism serving to actuate said raising means after said devices are in operative 60 positions.

19. In a dumping device for vehicles having an underframe and a dump body adapted 65 to tilt thereon for side dumping, devices

to engage the underframe and hold the same against movement during dumping, devices to raise one side of the dump body for dumping, means to simultaneously position said holding and raising devices, and 70 devices actuated in unison with said raising devices to lock said dump body to said raising devices to prevent upsetting of the dump body during dumping.

20. A dumping device for vehicles having 75 an underframe and a body carried thereby and adapted to be tilted for dumping, comprising devices for engaging the underframe and holding the same from movement during the relative tilting of the body, 80 said holding devices being movable into engagement with said underframe and out of engagement therewith into a position clear of said underframe for the entrance or removal of said vehicle with regard to said device, means to move said holding devices into and out of engaging position, and means to simultaneously position said holding 85 and raising devices.

21. In a dumping device for vehicles having 90 an underframe and a dump body adapted to tilt thereon for dumping, a bullwheel, means to rotate the bullwheel about its axis, a lift member pivoted to the rim of said bullwheel and adapted to be moved into and out of operative engagement with the dump body, said member being adapted during the rotation of said bullwheel in one direction to lift the body for tilting and during the rotation of the bullwheel in the opposite direction to lower the body from tilting position, a locking device to latch said member to said body, and means operatively connected to said locking device to move the same to locking position during 95 the first-mentioned rotation of said bullwheel.

22. In a dumping device for vehicles having 100 an underframe and a dump body adapted to tilt thereon for dumping, a bullwheel, means to rotate the bullwheel about its axis, a lift member pivoted to the rim of said bullwheel and adapted to be moved into and out of operative engagement with the dump body, said member being adapted during the rotation of said bullwheel in one direction to lift the body for tilting, and during the rotation of the bullwheel in the opposite direction to lower the body from 105 tilted position, a locking device to latch said member to said body, and a link pivoted to the bullwheel at a point eccentric to the pivot of said lift member thereon, said link being connected to said locking device to actuate the same during the rotation of said bullwheel.

23. In a dumping device for vehicles having 110 an underframe and a dump body adapted to tilt thereon for dumping, a bullwheel, means to rotate the bullwheel about its axis, 115

and a lift member carried by said bullwheel, said bullwheel in one position of rotation carrying said lift member free of the vehicle so the latter may be brought into place, said bullwheel during rotation bringing said lift member into lifting relation with said dump body and thereafter serving to lift and tilt

the same, said bullwheel thereafter serving to move said lift member to lower said body onto said underframe and to remove said lift member therefrom so the vehicle may be removed.

In testimony whereof, I affix my signature.

HENRY FORT FLOWERS.
